UNITED STATES PATENT OFFICE.

MELVILLE CLARK, OF CHICAGO, ILLINOIS.

REED-ORGAN.

SPECIFICATION forming part of Letters Patent No. 576,081, dated January 26, 1897.

Application filed March 26, 1896. Serial No. 584,976. (No model.)

To all whom it may concern:

Be it known that I, MELVILLE CLARK, a citizen of the United States, residing at Chicago, county of Cook, and State of Illinois, have invented certain new and useful Improvements 5 in Reed-Organs, which are fully set forth in the annexed specification, reference being had to the accompanying drawings, forming a part thereof.

10 This invention consists of improvements in the action of reed-organs and in the construction of reed-blocks.

The specific character of this improvement is set out in the claims.

15 In the drawings, Figure 1 is a vertical fore-and-aft section through the keyboard, reed-block, and wind-chest of an organ having my improvements, the action being shown in side elevation. Fig. 2 is a detail section at the

20 line 2 2 on Fig. 1, showing the rear side of the reed board or block, a portion of the reed-chamber being shown occupied by the reeds and others being shown empty. Fig. 3 is a section at the line 3 3 on Fig. 1, designed par-

25 ticularly to show the construction of the reed-chambers and showing the action in plan. Fig. 4 is a detail showing a modified link connection from the pneumatic to the valve.

One feature of my invention is especially 30 important in constructions in which the reeds comprise several sets, the corresponding individuals of which have their chambers in the same block, which is mounted on or in connection with the wind-chest, so that the

35 air-passages leading to said several individuals increase in length successively, the necessary length of the longest passage of the group being dependent, therefore, upon the number of reeds in the group. In all such

40 structures heretofore each reed has been provided with a separate passage leading from the wind-chest to its chamber or seat, and the number of sets of reeds which could be thus combined by mounting their corresponding

45 individuals in the same block has been found limited because the length of throat or passage from the wind-chest to the reed-chamber, consistent with making the reed speak properly, has been found to be quite closely

50 limited. It has been found, furthermore, that in such constructions, extending through four or five octaves, frequently all the reeds

will speak properly through, say, the lower three octaves and in the fifth octave, but will not speak at all in the fourth octave, although the conditions are apparently the same throughout the entire five octaves, and this is found to be the case without regard to the position of the several octaves—that is to say, if the fourth octave is transposed to the 55 position of the second the second octave will speak in the position in which the fourth octave refuses to speak, and the fourth octave will be mute in the position of the second, the failure to speak being thereby shown to 60 be dependent upon the pitch and not upon the position. On this account it has been found very difficult hitherto to construct reed-organs in which a large number of sets of reeds are mounted in the manner de- 65 scribed—that is, the corresponding individuals in the same block in rows transverse to the plane at which the block communicates with the wind-chest, and practically good-speaking quality has not been hitherto ob- 70 tained in such constructions wherein more than two sets of reeds were so mounted. Whenever a greater number of reeds has been thus mounted those more remote than the second are liable to be mute or weak in 75 speaking quality throughout at least one octave of the manual, and can be made to speak even feebly only by the utmost care and skill of the tuner.

It has been my aim to produce an organ in 80 which any number of sets of reeds may be assembled in the manner described, because the action which I have devised makes it possible to operate the valves suitably to control a large number of reeds with equal facility 85 and easy touch with which valves controlling a single set of reeds may be operated; and my invention, by means of which I am able to obtain this result—that is to say, to mount the corresponding individuals of the several 90 sets of reeds to any number in the same block without regard to the distance to which the more remote reeds are thereby removed from the wind-chest—consists in providing for all or a large number of the reeds controlled by 95 a given mute a single or common throat or air-passage from the wind-chest to the reed-chamber, instead of providing individual pas- 100 sages for each reed. This feature of my in-

vention, and the other features relating to the action, will be specifically apparent from the subsequent description.

In the drawings, A may represent the throat 5 of the bellows or exhaust-chamber.

B is the foundation-board above the bellows-throat A.

C is the wind-chest or vacuum-chamber. It is erected vertically at the rear of the 10 foundation-board, which is apertured at a to permit communication from the bellows-throat A to said vacuum-chamber C.

D, D', &c., are reed-blocks. I have shown two blocks, one for the reeds of the upper 15 half of the manual and the other for the reeds of the lower portion, as is usual, the several sets of reeds pertaining to the upper and lower portions being controlled by different mutes and stops to operate the same.

20 The description which will be given of one reed-block will answer for the other, or as many others as might be employed, according to the division of the control of the manual among the several stops.

25 The reed-block D is mounted on the forward side of the wind-chest C and is beveled upon its upper forward end, and through said beveled end the reed-chambers D', D², D³, and D⁴ open, the reeds d', d², d³, and d⁴ being 30 inserted vertically into their respective chambers through the openings of said chambers at the beveled upper surface of the reed-block. These reed-chambers, it will be understood, are individual, that is, one for each 35 reed, separated by proper partitions left in the block, both between the several chambers constituting one fore-and-aft group and between the several chambers of each row extending laterally and accommodating one 40 set of reeds; but from the lower ends of all the chambers pertaining to each set of reeds a single and common channel or furrow leads back to the rear vertical side of the block and through the forward wall of the wind-chest, 45 which is apertured to correspond with the position of the several channels which are denoted by the letters D¹⁰, D²⁰, D³⁰, and D⁴⁰, corresponding to the chambers D', D², D³, and D⁴, respectively. There is thus formed for 50 all or any desired number of the reeds of each set a single throat, whose width is not limited by the width of the reed or its chamber, and this single continuous throat is controlled within the wind-chest by a proper mute, the 55 several mutes being denoted by the letters D¹¹, D²¹, D³¹, and D⁴¹, respectively. Upon considering this structure it will be apparent that the extended throats thus formed give such perfectly free and unrestricted access 60 to each and every reed in the set that the depth or distance from the wind-chest proper out to the reed is of little consequence, because the throat is so large that it becomes in effect an extension of the reed-chest to the 65 very reed itself; and whatever causes have operated in the common construction to prevent the reed responding to the suction in

the wind-chest when such suction has to be transmitted through a deep narrow throat to the remote reed such causes are removed and 70 all the reeds, however remote in the block, are afforded equal opportunity to experience the suction when the valves which control the reeds, respectively, are opened.

In order to afford more frequent support 75 for the mutes than at the extremities merely, I bridge the throats D¹⁰, D²⁰, D³⁰, and D⁴⁰ at such number of points as may be found desirable, forming such bridges as seen at c, Fig. 3, in the forward wall of the wind-chest, 80 without, however, partitioning the throats themselves. It will be understood that it is not absolutely essential to the operativeness 85 of this feature for the purpose stated that all the reeds of a given set should have their throats combined in a common throat, the principle involved requiring only that enough of them should be so combined as to afford a widely-extended throat for each—that is, each reed having the benefit of the throat 90 made up of the sum of all the throats which are so combined. Practically the most convenient structure is to combine all the throats pertaining to the entire set of reeds controlled by the same mute.

95 I will now describe the action by which the reed-valves are operated.

E represents a key of the manual pivoted in the usual manner upon the key-frame E'.

F, F', &c., are levers corresponding to the 100 several keys of the manual, fulcrumed under the same in the bar F', having at their forward ends the buttons F², upon the upper end of which the keys operate to depress the forward ends of the levers. These levers are 105 shown "sprayed" for the customary purpose of affording more space laterally for each reed than is occupied by the key corresponding thereto.

G, G', &c., are the reed-valves. They are 110 pivoted at their upper rear portions on the forward wall of the wind-chest, each valve covering the reed-chambers of the entire fore-and-aft group corresponding to the single key of the manual. The valves are thus adapted 115 to seat by gravity upon the upper inclined face of the reed-block, covering the mouths of the reed-chambers opening therethrough. For a purpose which will be explained I project from each valve a rigid finger G', which 120 extends forward nearly horizontally when the valve is seated, overhanging the rear end of the corresponding lever F and at some distance above the same. Each of said levers F is provided with a rigid finger or offset F³, 125 which extends upward and makes contact with the lower side of the rigid finger G' of the valve, said contacting parts being suitably provided with felt terminals to prevent sound at their contact. The point of contact 130 of these fingers F³ and G' when the valve is set and the key undepressed is approximately in line with the fulcrum of the lever and the pivot of the valve. From this it results that

no perceptible or appreciable sliding movement occurs between the two fingers when the key is depressed and the valve is lifted, and this is primarily the purpose of dividing the two parts—to wit, valve and lever, extending in the direction and to the point stated. In the case of the widely-sprayed levers it is true there is a very slight lateral sliding, due to the fact that the lever moves in a vertical plane oblique to the vertical plane in which the valve swings, but this movement is very slight and scarcely perceptible. Springs f are provided for each of the levers F , tending to return them to their normal position after they are depressed by the keys, and thereby to return the keys to horizontal position after depression. The purpose of these springs is to quicken the return action of the key and lever and so permit the quick return of the valve, which might otherwise be retarded by the other parts.

H is a stop-bar which extends horizontally from side to side of the instrument across the row of valves G and far enough above them to arrest the valves in their opening movement. This stop-bar, being suitably covered with felt to prevent noise, operates by this means as a reflecting-spring, causing the valve, when thrown open by a quick depression of the key, to rebound from the stop-bar, and so making the valve respond to the most rapid touch which can be given the key as effectually as if it were seated by a spring instead of by gravity.

35 I design to operate the organ embodying these features automatically by pneumatics as well as by the manual. I mount the pneumatics, one of which appears (indicated by the letter K in Fig. 1) upon the forward side 40 of the wind-chest above the valves, respectively, and in front of each pneumatic I provide a bell-crank-lever L , fulcrumed at its angle, having one arm extending upwardly and connected by a link L' to the end of the 45 pneumatic behind it, while the horizontal arm, which projects forward, is connected by the link L^2 to the finger G' of the valve to which it corresponds below it. The pneumatic action constitutes no part of the present invention, and is therefore not shown in detail. M , however, is the tracker-range, over which the perforated strip N is actuated in any customary manner, flexible tubes P leading from the ducts of the tracker-range 50 to the primary pneumatics, which are located in the vacuum-chamber or wind-chest, and which, by mechanism not illustrated, operate by valves not shown, which control the motor-pneumatics above mentioned.

60 In connection with my improved action, as above described, I employ another improvement relating to the supporting of the manual-frame E' . This frame is supported at as many points as may be necessary by screw-threaded posts $E^2 E^3$, rooted in the foundation-board B , and penetrating the manual-frame and provided with stop-nuts $E^{20} E^{30}$,

respectively below and above the manual-frame, by which the latter may be adjusted and secured at each of the points at which such post is located, and thereby may be perfectly leveled and adjusted to give perfect contact of all the keys with their respective levers.

I prefer to inclose the reed-block and valves by swells at the forward side, upper side, and right and left hand ends, and most conveniently the pneumatics and connections therefrom to the reed-valve, and the rear ends of the valve-actuating levers are also inclosed.

R , &c., are the slats constituting the swell at the forward side. $R' R'$, &c., are slats constituting the swell at the top, and $R^2 R^2$, &c., represent slats constituting the left-hand end, precisely similar construction being employed at the right-hand end. (Not illustrated.) Any convenient stop mechanism may be employed to operate these swells, and I prefer to provide separate stops for each of them—that is, for the front, for the top, for the right-hand end, and for the left-hand end—so that the volume of tone may be graduated by operating simultaneously one or more, and so that by selecting the particular swell to be operated the tone may be delivered upward or forward, or to the right or to the left, or both. The right and left hand swells will have the special further distinction that the former will operate to the advantage of the upper half of the manual, while the latter will operate to the advantage of the lower half or bass portion. For the purpose of operating these swells I have shown the slats of each series connected by tapes $S S$, &c., the stop-rods $T T$, &c., operating on the last slat at one end of the series and a suitable spring S' being provided at the remote end. The stop-rods will be fitted in their slide-bearings closely enough to be held in whatever position they are set against the retracting effect of the spring, and the several swells may thereby be set open to any desired degree.

In order that the connection between the pneumatic and reed-valve may be such as to at all times prevent lost motion and lead to a prompt response of the reeds to the action of the pneumatic, I make the link L' , which connects the pneumatic to the upwardly-extending arm of the bell-crank lever, of a wire whose forward end is threaded and penetrates the bell-crank lever and is provided with a raw-hide nut L^{10} in front of the lever-arm, which, being screwed up onto the threaded wire link, will take up any lost motion and adjust the parts as desired. For a similar purpose of adjusting the parts and preventing any lost motion I may make the link L^2 of cord, preferably silk fish-line, and connect it to the reed-valve by a loop formed at the end of the cord, which is hooked into a screw-eye L^{20} , which is screwed into the finger G' of the valve, and which may be screwed into and through it at any depth to take up the slack

of the cord. This construction is shown in Fig. 4. One special advantage of the adjustable connections from the pneumatic to the valve above described is that by means thereof I can so adjust the valve that while actually seated it shall not be pulled down hard onto its seat, as it is liable to be by the suction from within the wind-chest, and which, if allowed to operate in this manner, is liable to make the valve difficult to operate. This is prevented by shortening up the links L' and L² by means of the adjusting devices provided, so that each valve is able only to come to its seat and not to be compressed onto it.

I claim—

1. In a reed-organ, a reed-block having formed in it a plurality of chambers for reeds pertaining to the same set, such chambers being controlled by separate valves at the speaking side of the reed, and merging at the opposite of the reeds in a common throat leading from the reeds to the wind-chest.

2. In a reed-organ, a reed-block having formed in it chambers for reeds pertaining to a plurality of sets, the reeds of each set having extended groups of contiguous chambers merging in a common throat which extends from the reeds to the wind-chest, and mutes which control said passages at their emergence into the wind-chest.

3. In a reed-organ, a reed-block having individual chambers for reeds pertaining to a plurality of sets, corresponding individuals of such sets having their chambers having openings at an exterior surface of the block in transverse rows, and valves which control said rows, respectively, of openings; the chambers pertaining to the several sets of reeds having extended groups of their contiguous individuals merging at the side of the reeds toward the wind-chest in throats or passages common to all the individuals of such groups respectively, and extending from the reeds thereof to the wind-chest, and mutes which control said throats at their openings into the wind-chest.

4. In a reed-organ, in combination with the wind-chest, a reed-block mounted thereon and having chambers for reeds pertaining to a plurality of sets; those of the several sets being arranged in rows which are successively more and more remote from the wind-chest, the throats or passages from the inner ends of said reed-chambers leading to the wind-chest; extended groups of the reed-chambers of the several sets respectively having a common or

single throat or passage-way whose lateral extent is total the lateral extent of all the reed-chambers of such group.

5. In a reed-organ, in combination with the wind-chest erected vertically, a reed-block mounted upon one of the vertical sides thereof, having its upper end beveled or sloping down from the wall of the wind-chest; reed-chambers pertaining to a plurality of sets of reeds formed vertically in such block and arranged set by set in rows which are successively more and more remote from the wind-chest, such chambers emerging through such sloping surface, and throats or passages from their lower ends respectively leading into the wind-chest; extended groups of contiguous reed-chambers in the respective sets having their throats or passages to the wind-chest merged in one, commencing directly at the side of the reeds toward the wind-chest.

6. In a reed-organ, in combination with the manual, the wind-chest erected vertically at the rear thereof; the reed-blocks mounted upon the forward side of the wind-chest and having upper sloping sides, through which the reed-chambers emerge, and the valves seating by gravity thereon, said valves having rigid fingers extending forwardly; the levers operated by the keys of the manual having rigid fingers extended upwardly against said forwardly-extending fingers of the valves, the contact-point between said lever-fingers and valve-fingers being approximately in the plane which contains the fulcrums of the levers and the pivots of the valves, whereby the swinging movement of said levers and valves about their respective pivots causes the minimum sliding movement of the fingers upon each other at the point of contact.

7. In a reed-organ, in combination with the manual, the wind-chest erected vertically at the rear thereof; the reed-block mounted at the forward side of the wind-chest and the valve seating by gravity on the reed-block, the levers actuated by the keys of the manual and actuating the valves by an upward stroke, and the elastically-cushioned check-bar extending above the valves adapted to limit the opening movement of the same and reflect them back to their seats elastically.

In testimony whereof I have hereunto set my hand, in the presence of two witnesses, at Chicago, Illinois, this 21st day of March, 1896.

MELVILLE CLARK.
